UNITED STATES PATENT OFFICE

140,229

DESIGN FOR A COMBINED HANDBAG AND CIGARETTE CASE

Joseph L. Friedman, New York, N. Y.

Application December 21, 1944, Serial No. 117,013

Term of patent 3½ years

(Cl. D87—3)

To all whom it may concern:

Be it known that I, Joseph L. Friedman, a citizen of the United States of America, residing in New York city, county of New York, and State of New York, have invented a new, original, and ornamental Design for a Combined Handbag and Cigarette Case, of which the following is a specification, reference being had to the accompanying drawings, forming part thereof, wherein,

Figure 1 is a front elevational view of a combined handbag and cigarette case showing my new design.

Figure 2 is an end elevational view.

Figure 3 is a top plan view, and

Figure 4 is a front perspective view of the combined handbag and cigarette case, drawn on a larger scale.

The rear of the combined handbag and cigarette case is substantially the same in appearance as the front, except for the omission of the closure member.

I claim:

The ornamental design for a combined handbag and cigarette case, substantially as shown and described.

JOSEPH L. FRIEDMAN.
